TYPE BAR AND INTERCHANGEABLE TYPE THEREFOR

Carl E. Redmond, Elmira, N. Y., assignor to Sperry Rand Corporation, New York, N. Y., a corporation of Delaware

Application February 28, 1956, Serial No. 568,389

14 Claims. (Cl. 197—36)

This invention relates to type bars, as used in typewriters, and in particular to type that can be interchangeably used in connection with said type bars.

A particular object of the invention is to provide a combination type bar and type element structure for use in a typewriter or like printing machine whereby type elements for printing the date or other data at a single operation may be readily changed.

A further object of the invention is to provide a readily detachable type element that is so mounted on the type bar that it will be self-seating and provide a cushioned floating effect for proper impact with the platen and one which can be replaced with a minimum of effort and without the need of special tools.

Other objects of the invention include the production of a type bar and type element combination of interchangeable nature having the advantages of economy of manufacture; simplicity of parts; ease with which the type may be attached to or removed from the type bars; precision with which the types can be assembled on the type bars; and rigidity of the types relatively to the type bars.

Other objects and structural details of the invention will be apparent from the following description when read in connection with the accompanying drawing, wherein

Fig. 1 is a face view of a type head shown in position on the outer end of a type bar;

Fig. 2 is a view in side elevation of the type head and the outer end of the type bar shown in Fig. 1 and illustrating the means for detachably securing the two together;

Fig. 3 is a view of the outer end of the type head and type bar showing the relation therewith of a clip means;

Fig. 4 is a section taken on the line 4—4 of Fig. 3 showing the relation of the parts;

Fig. 5 is a view in perspective showing the exploded relation of the parts;

Fig. 6 is a view in perspective showing the members in partly assembled relation;

Fig. 7 is a view similar to Fig. 1 showing the use of two separate type heads on the end of one type bar;

Fig. 8 is a side view showing the relation of the two type heads illustrated in Fig. 7 and the attachment thereof to the type bar;

Fig. 9 is an end view of the type head and type bar combination shown in Fig. 8 illustrating the relative position of the parts;

Fig. 10 is a view similar to Fig. 2 showing how the type head can be removed, by the use of an implement, from its position on the end of the type bar;

Fig. 11 is a view similar to Fig. 10 showing the type head in a partially detached position with respect to the type bar;

Fig. 12 is a view similar to Fig. 10 showing a modified form of tool and means for securing the clip in place;

Fig. 13 is a section taken on the line 13—13 of Fig. 12 showing the shape of the end of the detaching tool;

Figs. 14 and 15 are, respectively, full and sectional

2

views showing various means for securing the clip in place; and

Fig. 16 is an end view of the structure shown in Fig. 15.

Referring to the drawings in detail and in particular to Figs. 1 to 6, 10 indicates a type bar of novel form including a shank 11 and an enlarged outer striking end 12 which is provided with a cylindrically shaped drive-fitted stud 13 extending toward the observer and located near a heel or guide portion 14 formed in said end of the type bar. The edge of the latter that carries a type element 15 is finished with a flat side edge face 16 in which a rectangular notch is cut as at 17. The free end of the type bar is slotted as at 18 inwardly from the end face 19 thereof to a point beyond the mid-portion of the face 16, while the back edge of the bar presents the usual projection or stop 21 for preventing damage to the type when type bars accidentally pile up during the typing action. One side wall of the slot 18 is provided with a lateral semi-circular recess or seat 22 about mid-way of the slot for receiving a semi-circular flute or crimp 23 formed in the flexible tongue 24 of a yoke clip 26 used in securing the type element 15 in place on the end of the type bar. The tongue 24 is an integral part of the clip 26 and flexes to cause the ridge or crimp 23 to seat in the recess 22 when the bottom of the clip is forced into the slot 18. The flat material, from which the clip is made, is punched out as at 27 to form the flat tongue 24 with its crimp or flute 23, and then bent arcuately as at 28 to provide opposed converging sides or wings 29 having rounded outer ends and axially aligned hemispherical protuberances 31 directed inwardly to form gripping nubs for engagement with the type element 15. The converging wings, as shown in Fig. 5, are gradually spread apart by the type element and have a degree of flexibility that exerts a gripping action on the latter as it is forced down into position on the end of the type bar.

The type element 15 is cast or otherwise shaped to provide one or more characters or words 32 on the facing 33 thereof which is formed integrally with the body 34 thereof. The latter is substantially rectangular in shape, having tapered sides 36 forming a central slot 37 into which the end 12 or head of the type bar fits with clearance when the type element is attached thereto. The side walls of the type are provided with axially aligned pockets 38 on the tapered walls of which the projections or nubs 31 are self-seating. The corners of the body 34 are rounded as at 39 and the free edges are bevelled as at 40 so that the taper of the outer sides 36 of the body 34 coact with the bevels 39 to spread the jaws 29 of the clip 26 when the type bar is saddled by the type element. The end edge of both sides 36 is provided with a semi-circular recess 41 which fits about one side of the stud 13, the latter serving as a guide and also means for preventing displacement of said type element. The inner top wall of the slot 37 is provided with a depending key 42 which fits into the notch 17 of the type bar in order to insure proper alignment of the type and type bar. The width of the face of the type element may vary for special words or characters but in all instances the facing 33 at its opposite edges extends beyond the upper extremity of the body to provide flanges 43. When the type element is to be changed, Figs. 10 and 11, a suitable tool 44 is used having spaced prongs 46 which underlie the flanges 43 of the type element when the heel 47 of the tool rests on the upper flat face 16 of the striking end of the type bar. The leverage afforded by the short pronged end of the tool requires little effort to snap the element 15 out of the grip of the yoke clip 26, after which it can be easily removed by the fingers and another type element snapped into place. Change of elements does not require the removal of the clip from

the type bar and one of the functions of the tongue 24 is to prevent the clip from slipping out of the slot 18 of the type bar during the replacing operations.

In Figs. 7, 8, and 9 the type bar 50 is adapted to hold two type elements 51 and 52, and is provided with a cylindrical or full guide or hinge stud 53 and a semi-cylindrical or half guide stud 54. The latter provides the clearance necessary to allow the type 51 to be swung about its stud 53 when it is being removed and also makes it possible to space the type elements the proper distance vertically of the characters thereof. The type bar 50 is shaped to provide an enlarged striking head 56 which is slotted inwardly as at 57 from its outer end and parallel to a flat face 58 which has spaced notches 59 therein for the reception of suitable keys 61 projecting from the bottom of the slot 62 formed in each type element. The sides 63 of each type element are provided with pockets 64 or depressions into which seat the nubs 66 of the clips 67. The latter may or may not be provided with tongues as is the clip 26, but are substantially U-shaped and are tempered so that the sides thereof converge to provide gripping jaws for holding the type elements in place. The sides of each type element are tapered and the edges bevelled as described in connection with the element 15 so that the type can be snapped into place with a minimum of effort.

Suitable clearances are provided between the top of the slots in the type elements and the finished face of the type bar, so that when the form of clip 26 is used the tongue 24 provides a cushioning effect when the type strikes the platen, and the combined action of said tongue and the trunnion effect of the nubs makes the type self-seating at platen impact so that a clear type impression is produced. The type elements of each form have recesses for the studs in each side and the studs have a drive fit with a hole in the type bar so that the stud can be used at one side of the type bar or the other to engage the type elements as used on the right or left hand type bars. The clips may be secured in place by the swaged spots 65 which crowd the metal of the slot and block exit of the clips.

In the form of the invention shown in Figs. 12 and 13, the clip 70 is made the same as the clip 26 except for the tongue 24. It is fixed in place in the slot 71 of the type bar 72 by swaging the metal of the type bar as at 73 to crowd the metal of the type bar and jam the clip in place. A shoulder or flange 74 formed at the ends and sides of the type element 76 permits the use of a simplified pick-off tool 77 whose legs 78 can be spread so that the turned lower ends 79 thereof, notched as at 80, can snap beneath the flange 74 of the type element. When the tool is rocked in counterclockwise direction the type is lifted out of engagement with the clip and can be readily removed from the type bar.

In Fig. 14 the clip 81 is held in place by a spot of solder 82, and in Fig. 15 the method of fixing the clip 83 in the slot 84 is by swaging the outer edges of the material at the end of the slot as at 85. This figure also illustrates the clearance between the sides and bottom of the key 86 of the type 87 and the notch 88 so that the "floating" effect of the type is obtained, particularly when a clip, having a tongue, is employed.

It is to be noted that the clip 26 with its tongue 24, can be used in the slot 84 which does not need to be recessed as at 22, with the end of the slot being restricted as by swaging 85 so that the cushioning effect of the tongue gives further floating and self-seating advantages to the type mounting.

While I have described what I consider to be highly desirable embodiments of my invention, it is obvious that many changes in form could be made without departing from the spirit of the invention, and I therefore, do not limit myself to the exact forms herein shown and described nor to anything less than the whole of my invention as hereinbefore set forth, and as hereinafter claimed.

What I claim as new, and desire to secure by Letters Patent is:

1. In combination: a type bar having a striking end shaped to provide side and end edges and a slot opening inwardly from said end edge; a type element fitting over said side edge and having depending portions flanking the opposite faces of said striking end; a clip in said slot having jaw members for yieldable gripping engagement with the depending portions of said type element for holding the latter in place on the type bar; and means for securing said clip in said slot.
2. In combination: a type bar having a striking end shaped to provide a side edge, an end edge and a slot opening inwardly from said end edge and having a seating groove in a wall of said slot; a type element fitting over said side edge and having depending portions flanking the opposite faces of said striking end; a clip in said slot having jaw members for yieldably gripping said type element to hold the same in place; and a tongue on said clip engaging the seating groove of said slot to secure said clip in the slot.
3. In combination: a type bar having a striking end shaped to provide side and end edges, a slot opening inwardly from said end edge and a stud projecting from one of the opposite side faces of said striking end; a type element fitting over said side edge and having depending portions flanking said opposite side faces, and one of said portions being recessed for holding engagement with said stud; a clip in said slot having jaw members for yieldably gripping engagement with the depending portions of said type element for holding the latter in place on said type bar; and means for securing said clip in said slot.
4. In combination: a type bar having a striking end shaped to provide side end edges and a slot opening inwardly from said end edge and a groove in one wall of said slot; a type element fitting over said side edge and having depending portions flanking the opposite faces of said striking end, said portions having recesses constituting axially aligned seats; a clip in said slot presenting jaw members and a yieldable tongue for engaging said groove; and axially aligned protuberances on said jaw members for gripping engagement with said seats for holding the type element in place on the type bar.
5. In combination: a type bar having a striking end shaped to provide side and end edges and a slot opening inwardly from said end edge; a type element fitting over said side edge and having depending portions flanking the opposite faces of said striking end, said portions having axially aligned recesses; a clip in said slot presenting opposed jaw members; axially aligned projections in said jaw members for detachable gripping engagement with the recesses of said depending portions for holding the type element in place on the type bar; and means for securing the clip in said slot.
6. In combination: a type bar having a striking end shaped to provide face and end edges a slot opening inwardly from said end edge and a notch opening inwardly from said face edge; a type element fitting over said face edge and having a key for engagement with said notch, said type element also having tapered depending portions flanking the opposite faces of said striking end and said portions having recesses; a clip in said slot presenting opposed jaw members adapted to be spread under gripping tension by the tapered depending portions of the type element when the latter is forced into said clip; and projections on the jaws of said clip adapted to seat in the recesses of the type element to secure the latter in place on the type bar.
7. In combination: a type bar having a striking end and shaped to provide side and end edges and slots opening inwardly from each of said edges; a type element fitting over said side edge and having a depending key for engagement with the side edge slot and depending portions flanking the opposite faces of said striking end; a

clip in said end edge slot presenting jaw portions for gripping engagement with the depending portions of said type element; and means for securing said clip in said slot.

8. In combination: a type bar having a striking end shaped to provide side and end edges and a slot opening inwardly from each of said edges, the slot of the end edge having a lateral groove in one wall thereof constituting a seat; a type element fitting over said side edge and having depending portions flanking the opposite faces of said striking end and extending into the slot of said side edge; a clip in said end edge slot having jaw members for yieldably gripping said type element to hold the same in place; and a tongue on said clip engaging said groove to secure the clip in the slot and provide a yieldable floating action for said type element.

9. In combination: a type bar having a striking end shaped to provide side and end edges and a slot opening inwardly from said end edge and disposed parallel to said side edge, said slot having a lateral groove in one wall thereof constituting a seat; a type element fitting over said side edge and having depending portions flanking the opposite faces of said striking end and axially aligned recesses in said portions; a clip in said slot having jaw members; projections on said jaw members engaging said recesses for yieldably gripping said type element to hold the same in place; and a tongue on said clip engaging said groove for holding the clip in said slot.

10. In combination: a type bar having a striking end shaped to provide side, end edges and a slot opening inwardly from said end edge and a lateral groove in one face of said slot; a type element fitting over said side edge and having depending portions flanking the opposite faces of said striking end, said portions having seating recesses and being bevelled along the lower edges thereof; a clip in said slot presenting a tongue for yieldable engagement with said groove and also opposed jaw members adapted to be yieldably spread under gripping tension by the bevelled edges of said depending portions when the type element is forced into said clip; and projections on the jaws of said clip adapted to seat in said seating recesses of the type element to detachably secure the latter in place on the type bar.

11. In combination: a type bar having a striking end shaped to provide a side edge and an end edge having a slot opening inwardly therefrom; clips in said end edge slot each presenting jaw portions; spaced type elements fitting over said side edge and each presenting recessed depending portions flanking the opposite faces of said striking end and fitting between the jaws of the clips, said clips having projections for engaging the recesses of said

depending portions; and means for securing said clips in said slot.

12. In combination: a type bar having a striking end shaped to provide a side edge having a plurality of notches therein and an end edge having a slot opening inwardly therefrom, spaced studs extending from one face of said end; clips in said slot each presenting jaw portions and projections on said jaw portions; spaced type elements fitting over said side edge and each presenting depending portions flanking the opposite faces of said striking end and fitting between the jaw portions of the clips; keys in said elements fitting into said notches, the depending portions being recessed to provide seats for said studs and the projections of said jaw portions; and means for securing said slips in said slot.

13. In combination: a type bar having a striking end shaped to provide side and end edges and a slot opening inwardly from said end edge; a type element fitting over said side edge and having a flanged facing and depending portions flanking the opposite sides of said striking end; a clip in said slot having jaw members for yieldable gripping engagement with the depending portions of said type element for holding the latter in place on the type bar; and means for securing the clip in said slot, said side edge of the striking end and the flange of the facing coacting with a tool placed therebetween to facilitate release of the type element from said clip.

14. In combination: a type bar having a striking end shaped to provide a side edge having a notch therein, an end edge having a slot therein and a stud having a drive fit in said end for projection from either face thereof; a type element fitting over said side edge and having tapered depending portions flanking the opposite sides of said striking end, said portions having seating recesses and being bevelled along the lower edges thereof and being also provided with edges recesses for engagement with said stud; a key in said type element engaging the notch in said side edge; a clip in said slot having type element clamping jaw members; projections on said jaw members for yieldable engagement with said seating recesses when the jaws are spread by the bevel and taper of said depending portions when the type element is positioned for use; and means for securing said clip in the slot.
